(57) **CLAIM**

The ornamental design for sound reproduction equipment, as shown and described.

DESCRIPTION

FIG. 1 is a perspective view of sound reproduction equipment showing our new design;

FIG. 2 is a right side elevational view showing the sound reproduction equipment of FIG. 1;

FIG. 3 is a left side elevational view showing the sound reproduction equipment of FIG. 1;

FIG. 4 is a front elevational view showing the sound reproduction equipment of FIG. 1;

FIG. 5 is a rear elevational view showing the sound reproduction equipment of FIG. 1;

FIG. 6 is a top elevational view showing the sound reproduction equipment of FIG. 1; and,

FIG. 7 is a bottom elevational view showing the sound reproduction equipment of FIG. 1.

The broken line shown in the drawings illustrate portions of the sound reproduction equipment that form no part of the claimed design.
